ELMER A. ERMOLD, OF PHILADELPHIA, PENNSYLVANIA, ASSIGNOR TO WIRT COMPANY, OF PHILADELPHIA, PENNSYLVANIA, A CORPORATION OF MAINE.

LIGHTNING ARRESTER.

Application filed November 20, 1925. Serial No. 70,233.

This invention relates to apparatus for use in conjunction with electric circuits to protect apparatus connected in such circuits and to discharge static electricity which may accumulate from the atmosphere or result from lightning discharges.

The invention has for its object to provide a lightning arrester in which the circuit members or electrodes are completely enclosed within and protected by insulating members which are capable of being easily connected or disconnected, the parts thereof being so arranged that the fixed adjustment of the electrodes may be readily changed if found necessary upon final testing of the instrument.

Another object is to provide a lightning arrester which may be easily and permanently secured to a supporting wall to present a neat appearance.

When an outdoor aerial is employed in operating a radio receiving circuit, a lightning arrester is preferably connected across the aerial to ground between the aerial and the receiving circuit to serve as a means of discharging static electricity which may accumulate from such sources as lightning. A general form of lightning arrester for such a use is shown in the accompanying drawings; its action depends upon the tendency of a disruptive or impulsive discharge of electricity to traverse an alternative path including an air gap, rather than a longer, though better conducting, path and the length of the included air gap determines the minimum voltage from which the instrument will provide protection. It is essential, therefore, that the fixed air gap in a given arrester have the proper value to afford the protection for which the instrument was designed. Consequently provision for adjusting or regulating the fixed air gap in an arrester is preferably included in the construction.

Other general characteristics which are desirable in lightning arresters are compactness, ruggedness, and simplicity of construction. In addition lightning arresters which are adapted for use in the protection of radio receiving sets are preferably so constructed that they can be easily and permanently secured to the exterior of a building, for ex-

ample, to present an appearance which is neat, orderly and in harmony with other exterior fixtures for buildings.

The present invention provides a lightning arrester which possesses the various essential characteristics outlined above and is well adapted for use across an outdoor aerial employed with a radio receiving circuit.

Briefly this is accomplished by constructing a lightning arrester composed of tubular members of such forms as to be readily assembled and having conducting members projecting axially inward with their ends approaching contact at a point on one side of the meeting plane of the tubular members. With this construction the air gap may be readily increased or decreased as is required in view of the final testing of the instrument.

Another feature of the invention comprises a flange or shoulder located on the exterior of one of the tubular members and adapted to support a bracket without danger of arcing between the instrument and the bracket during a storm.

The invention will be more thoroughly understood with the aid of the description to be given in connection with the accompanying drawings in which:

Fig. 1 is a side view of a lightning arrester constructed in accordance with the invention.

Fig. 2 is a bottom view of the arrester shown in Fig. 1.

Referring to the drawings, a lightning arrester constructed in accordance with the invention comprises upper and lower tubular members 3 and 4 preferably composed of an insulating and waterproof material such as a molded phenol condensation product and current conducting members or electrodes 6 and 7 extending axially in opposite directions from the ends of the tubular members and rigidly secured to these members during the molding process, to which end the electrodes are provided with knurled annular ridges, as shown. Since the lightning arresters are commonly secured to the exterior of buildings and are therefore subject to the action of storms and moistures, the members 3 and 4 are preferably so constructed and joined as to prevent the entrance of foreign materials and particularly moisture or liquid into the en-

closure 5. To this end, the members 3 and 4 are closed at one end and sealed at their open ends by giving the upper member an internal thread and the lower member a corresponding external thread. As a further means of insuring the protection of enclosure 5 from moisture and particularly during storms, the upper closed end of the upper member is provided with a petticoat 10 which may be formed thereon during the molding process.

In accordance with a feature of the invention, the electrodes 6 and 7 extend axially in opposite directions from the ends of the members 3 and 4, their ends approaching contact at a point wholly within one of the tubular members. In the embodiment shown herein, the electrode 7 projects from the lower tubular member and extends beyond the plane of meeting of the members 3 and 4, thereby placing the air gap between the electrodes beyond said meeting plane and wholly within the upper member 3. With this arrangement of parts, the fixed spacing between the ends of the electrodes may be readily increased by shortening electrode 7 at its free end, or decreased by reducing the length of the upper part 3 at its open end. It will be obvious, however, that electrode 6 may be made to extend to a point within the lower part if desired, as an alternative form for the embodiment illustrated.

When a lightning arrester is placed in the open or exposed to the elements, as on the exterior of a building, arcing during storms between the lead-in terminal 8 and the supporting device may be encountered when the petticoat 10 is wet or these elements become disarranged and said terminal is in close proximity to the supporting bracket. In order to obviate this difficulty, provision is made whereby the body of the arrester cannot slip down on its supporting member or bracket 11, by forming a flange or shoulder 12 on the lower member 4. The flange may conveniently be formed by reducing the diameter of the lower member as shown to fit the eye of the bracket. With this arrangement of the parts the instrument may be securely supported so as to have an air gap of definite fixed length between the lower edge of the petticoat 10 and the bracket 11, thereby substantially eliminating all danger of arcing across the outer surface of the insulating member.

In using the lightning arrester to protect a radio receiving circuit for example, it is connected by means of binding posts or terminals 8 and 9 from the aerial lead to ground between the aerial and the set. The instrument thus serves as an alternative path over which the usual currents of comparatively small voltage will not pass but which will be traversed readily by disruptive or impulsive discharges of the electricity accumulated in any manner by the exposed wires and lead-in with which the device is associated. Since

the length of air gap determines the minimum voltage which will be passed to ground instead of going through the circuit, the limits of the suitable air gap length will be determined by the particular conditions to be met in each instance.

Various means of supporting the arrester per se may be employed and in the drawings I have shown the bracket as composed of a single strip of sheet metal bent to form a circular eye 13 embracing the lower insulating member 4 and from which extend the parallel arms 11, 11 at the extremities of which are the oppositely projecting feet 14, 14 by means of which the bracket may be secured to a wall or other support. Adjacent the eye, the arms of the bracket are spread apart a short distance as shown to permit them to be tensioned by a screw 15 for the purpose of contacting the band portion 13 to firmly clamp the insulator 4.

From the arrangement of parts described it will be seen that the device comprises a minimum number of parts of simple construction, which may be readily assembled for testing and capable of being quickly adjusted, by grinding away either the end of the electrode or the end of the wall of one of the outer enclosing members, if it is desired to increase or decrease the air gap between the electrode.

In accordance with the provisions of the patent statutes the principle of the invention has been described, and illustrated by the portrayal of a structure which in practice has proved to be a satisfactory embodiment thereof, but it is desired to have it understood that the structure shown is merely illustrative, and that the invention may be carried out in other ways.

The invention having been described, what is claimed as new and desired to be secured by Letters Patent is as follows:

In a lightning arrester for radio signal receiving aerials, the combination with a lower molded tubular insulating member closed at its lower end and having an exteriorly threaded portion at its upper end, and an annular flange located below said threads the lower surface of which co-operates with a supporting bracket, of an upper molded tubular insulating member closed at the top and having interior screw threads engaging those of the lower member, the open end of said upper member engaging the upper surface of said flange to limit its movement on the lower member, current conducting posts disposed axially within said members and of such relative lengths that their inner ends are adjacent but dielectrically separated at a point above the plane of the end of said lower member whereby the gap between the adjacent ends of said posts can be increased by shortening the end of the post projecting beyond the lower member or decreased by cut-

ting away the end face of the upper member, said posts being imbedded in the members at their outer ends during the molding process, to provide solidity thereby insuring a permanent setting of the gap between the posts and to prevent the entrance of moisture within the members, said posts also having

provision exteriorly of said members for effecting wiring connections to an aerial and ground.
